CLAIM

The ornamental design for a lathe as shown and described.

DESCRIPTION

1. Lathe

1.1 : Perspective

1.2 : Perspective

1.3 : Front

1.4 : Back

1.5 : Enlarged left view

1.6 : Enlarged right view

1.7 : Top

1.8 : Bottom

1.9 : Enlarged

1.10 : Enlarged

The broken lines in the reproductions depict portions of the lathe that form no part of the claimed design; fig. 1.9, 1.10 are the enlarged views of the portion taken at line 1.11, 1.12 in fig. 1.1, 1.2; the dash dot dash broken lines in the

(Continued)

reproductions represent boundaries for the enlarged views and form no part of the claimed design.

1 Claim, 10 Drawing Sheets
